UNITED STATES PATENT OFFICE.

HARRY G. STEELY, OF PIQUA, OHIO.

CORSET-COVER.

SPECIFICATION forming part of Letters Patent No. 656,754, dated August 28, 1900.

Application filed May 21, 1900. Serial No. 17,497. (No model.)

To all whom it may concern:

Be it known that I, HARRY G. STEELY, a citizen of the United States, residing at Piqua, in the county of Miami and State of Ohio, have 5 invented certain new and useful Improvements in Knit Garments for Female Wear; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 My invention relates to improvements in cut knit garments for female wear, and has special reference to that class of garments known as "corset-covers." The garment may, however, be worn either as a corset- 20 cover or as an undergarment. Heretofore knit garments of this character have been constructed with the same fullness at the back as in the front, owing to the impossibility of limiting the tuck or double stitch to a portion 25 only of the circumference of the material as it is made in the machine. By reason of this unnecessary fullness of the garment in the back more or less inconvenience has been experienced by reason of the garment lumping 30 or creating folds at the back under the pressure of the clothing.

It is therefore the object of the present invention to construct a cut knit garment of the character specified with the required fullness to the front only or that portion of the 35 garment fitting over the bust and providing a plain back or a back devoid of any fullness, as will hereinafter be more fully described.

In the drawings, Figure 1 is a front elevation of a cut knit garment made in accordance with my invention. Fig. 2 is an elevation of the back of said garment. Fig. 2^a is a rear perspective view of the garment. Fig. 3 is a perspective view of the material as it 45 comes from the knitting-machine and from which two of such garments may be constructed. Fig. 4 is a plan of the material cut for a garment.

The material, as shown in Fig. 3, is made 50 on a well-known form of circular-knitting machine and is formed by two well-known stitches—to wit, a cross or tuck stitch A and

a plain stitch B—the former stitch having more fullness than the latter, which is due to the use of a double thread in forming such 55 stitch. In forming the plain stitch B the needles cast off at every guide in the dial of the machine, and in forming the cross or tuck stitch A, which consists of a double thread, as before stated, the cast off is made at every 60 other guide in the dial, which is well known to those familiar with the art of knitting. In constructing a garment such as is shown in Figs. 1 and 2 this tuck-stitch A, which creates more fullness in the material than the plain 65 stitch, is placed in front of the garment to provide a proper fullness for the bust, while that portion B of the material made by the plain stitch forms the back of the garment and is devoid of such fullness. 70

In constructing a garment as above described the material, as shown in Fig. 3, which represents said material as it is taken from the knitting-machine, is cut longitudinally on two sides to make two equal parts. Each of 75 such parts is then given the necessary cut, as is shown in the diagram Fig. 4, is then folded over in the middle on line *xx* of Fig. 3 and is sewed, and is given the necessary ornamental trimming or edging C. The tuck- 80 stitch A may be given a greater depth than that shown in Fig. 1 to provide a sufficient fullness in front of the garment. Therefore it will be understood that the pockets or fullness shown at A in said figure may be varied. 85

Among the desirable features of the garment may be mentioned the facility with which a cut knit garment having the necessary fullness in front for the bust and a plain back may be made from knit material, and 90 whereby the necessity of sewing separate pieces for bust-pockets in front of the garment is avoided.

A garment constructed in accordance with the above description will fit snugly to the 95 body and may be worn with comfort, all unnecessary looseness being avoided.

Having described my invention, what I claim, and desire to secure by Letters Patent, is—

The herein-described cut knit waist garment consisting of two parts, a front and rear portion, the front portion of said garment comprising a transverse section of tubular fabric 100

knitted in two stitches, a tuck or double stitch, and a plain stitch, said section being cut open longitudinally to form the front portion of the garment, the rear portion of said garment being formed from a transverse section of tubular fabric knitted in plain stitch and cut open longitudinally, whereby the entire garment is elastic, but the breast portion of the

front is more elastic being formed by the line of tuck or double stitches, as set forth. ¹⁰

In testimony whereof I affix my signature in presence of two witnesses.

HARRY G. STEELY.
